UNITED STATES PATENT OFFICE.

YUILL WINCHESTER SMITH, OF ROZEL, KANSAS.

DESIGN FOR A GAME-BOARD.

52,996.

Specification for Design.

Patented Feb. 11, 1919.

Application filed February 3, 1917. Serial No. 146,531. Term of patent 7 years.

To all whom it may concern:

Be it known that I, YUILL W. SMITH, a citizen of the United States, residing at Rozel, in the county of Pawnee and State of Kansas, have invented a new, original, and ornamental Design for Game-Boards, of which the following is a specification, reference being had to the accompanying drawing, forming part thereof.

The figure is a plan view of a game board showing my new design.

I claim:

The ornamental design for a game board as shown.

YUILL WINCHESTER SMITH.

Witnesses:

J. H. RUDERER,
W. W. CHRISTIAN.
